J. E. JOHNSON

GALLEY FOR ADDRESS PLATES AND THE LIKE

Filed May 24, 1920

FIG. 1

FIG. 2

FIG. 3

FIG. 4

Attv. 5
Inventor
John E. Johnson
By Jones, Addington, Ames & Seibold
Atty. 5

UNITED STATES PATENT OFFICE.

JOHN E. JOHNSON, OF CHICAGO, ILLINOIS, ASSIGNOR TO THE SPEEDAUTOMATIC COMPANY, OF CHICAGO, ILLINOIS, A CORPORATION OF DELAWARE.

GALLEY FOR ADDRESS PLATES AND THE LIKE.

Application filed May 24, 1920. Serial No. 383,654.

To all whom it may concern:

Be it known that I, JOHN E. JOHNSON, a citizen of the United States, residing at Chicago, in the county of Cook and State of Illinois, have invented new and useful Improvements in Galleys for Address Plates and the like, of which the following is a full, clear, concise, and exact description, reference being had to the accompanying drawing, forming a part of this specification.

My invention relates to galleys for address plates and the like, and more particularly to a galley designed for use, especially in connection with the address plates used in automatic wrapping and addressing machines, such as are used in the mailing and addressing of newspapers, magazines and the like.

Address plate galleys of the character mentioned, when not in use, are stored in a cabinet provided for the purpose and it has been found that considerable time is lost in determining just what plates any particular galley contains, it being necessary, at the present time, to withdraw a galley and inspect the plates contained therein in order to obtain this information.

One of the objects of this invention is to provide a galley in which means will be provided for readily indicating the character of the plates contained in the galley without the necessity of removal of the galley from the cabinet in which the same is arranged.

A further object is the production of a galley of the character mentioned in which a movable stop will be provided to facilitate withdrawal of the address plates from the galley during use of the same in connection with a wrapping and addressing machine, and in which said stop will afford the desired indication or designation of the address plates arranged in the galley.

A still further object is the production of a galley characterized as above mentioned which will be of durable and economical construction and efficient in use.

Other objects will appear hereinafter.

With these objects in view, the invention consists in the combinations and arrangements of parts hereinafter described and claimed.

The invention will be best understood by

reference to the accompanying drawings in which—

Fig. 1 is a fragmental front elevation of a cabinet for address plate galleys, the front door of the cabinet being broken away to expose several of the galleys contained in the cabinet;

Fig. 2 is a top plan view of the front end of one of the galleys;

Fig. 3 is a front elevation of one of the galleys; and

Fig. 4 is a vertical longitudinal section taken on line 4—4 of Fig. 2.

The preferred form of construction, as illustrated in the drawings, comprises a galley which is formed of an elongated channel formed body 5, preferably constructed of sheet metal. Said galley body 5 comprises a bottom 6 and sides 7, the upper edges of said sides being formed with inwardly projecting portions or flanges which are adapted to engage with notches B in the address plates A which are used in connection with the galley, whereby said address plates are locked against accidental detachment from the galley.

Provided at one end of the galley body 5 is an angularly formed stop 8, one end of which is hingedly secured to the bottom 6 of the galley by means of a hinge pin 9. Said hinged end of said stop is wrapped around said pin 9, and the ends of the latter are engaged with depressed portions 10 formed in the bottom 6 through slitting thereof as clearly seen in Fig. 2. The free end of stop 8 is arranged to register with the end of the galley channel, the said end forming the stop proper, against which the address plates are adapted to rest and be supported, as will be readily understood. Said stop is normally held in operative position, that is, with the free end thereof in registration with the galley channel by means of a torsional spring 11 arranged upon the pin 9 and having its respective ends pressing against the galley bottom 6 and the member 8, as clearly seen in Figs. 2 and 4.

With this arrangement it will be seen that the spring 11 will yieldingly hold with the stop in its operative position, movement of the stop from such position being against the influence of the spring.

From the stop 8 is stamped or pressed a

lug 12 which forms a handle to facilitate withdrawal of the galley from the galley cabinet in connection with which the same is used. The handle 12 projects forwardly and is curved, as seen, for ready engagement with the finger, the outer end of said handle terminating in a plane above that of the bottom of the galley so that when the galley is placed upon a flat surface such as a table top, said handle will not prevent the galley lying flat.

Formed in the outer stop-forming portion of the stop member 8 is an opening 13 through which the address C upon the adjacent address plate arranged in the galley may be viewed in order to advise the user as to what plates are contained in the galley without the necessity of withdrawing the galley and inspecting the plates, as will be readily understood. By this slotting of the stop, the endmost address plate will serve also as a designation or indication card.

The outer portion of the stop 8 is also formed at its lateral edges with flanges 14 to permit of the employment, if desired, of a separate designation card D, as clearly seen in the upper portion of Fig. 1, the card, when so employed, being limited in its downward movement by the handle 12, a flange 15 at the upper side of the stop serving as a lock to hold the designation card in place. In order to remove the designation card, it is first required to flex or buckle the central portion thereof outwardly or forwardly in order to clear the stop 15, as will be readily understood.

With the construction set forth, then, it will be seen that a galley is provided in which, the same is arranged in a galley cabinet E, the same will be properly tagged or marked to advise as to the contents of the galley without the necessity of removing the galley to examine the plates to ascertain this fact. At the same time, a galley is provided in which the stop is movably mounted so that when the galley is arranged in operative relation with a wrapping and addressing machine, the stop may be moved to inoperative position, that is, out of registration with the address plate channel of the galley so as to permit of release of the address plates for entry into the machine.

While I have illustrated and described the preferred form of construction for carrying my invention into effect, this is capable of variation and modification without departing from the spirit of the invention. I therefore do not wish to be limited to the precise details of construction set forth, but desire to avail myself of such variations and modifications as come within the scope of the appended claims.

Having thus described my invention, what I claim as new and desire to secure by Letters Patent is:

1. A galley for address plates and the like comprising an elongated body having a channel for the reception of the plates; a stop movably secured to said body at one end thereof and arranged to be moved into and out of registration with said channel; means associated with said stop for displaying matter descriptive of the plates arranged in said body, and spring means for normally retaining said stop in registration with said channel.

2. A galley for address plates and the like comprising an elongated body having a channel for the reception of the plates, an angularly formed sheet metal stop hingedly secured to the underside of said body adjacent one end thereof, said stop comprising a horizontal portion bearing on the underside of said body and a vertical portion for registration with the end of said channel; struck up means associated with said vertical portion for displaying matter descriptive of the plates arranged in said body and a handle struck out from said horizontal portion and projecting forwardly from the lower edge of said stop, the outer end of said handle terminating in a horizontal plane above the plane of the bottom of said body.

3. A galley for address plates and the like comprising an elongated body having a channel for the reception of the plates, an angularly formed sheet metal stop hingedly secured to the under side of said body adjacent one end thereof, said stop comprising a horizontal portion bearing on the under side of said body and a vertical portion for registration with the end of said channel; struck up flanges associated with said vertical portion for receiving matter descriptive of the plates arranged in said body and a handle struck out from said horizontal portion and projecting forwardly from the lower edge of said stop.

4. A galley for address plates and the like comprising an elongated body having a channel for the reception of the plates, an angularly formed stop member at one end of said body, said stop comprising a normally horizontal portion bearing on the under side of said body and a normally vertical portion for registration with the end of said channel, and a spring hinge on the under side of said body for securing and for normally retaining said stop member in registration with said channel.

In witness whereof I have hereunto subscribed my name.

JOHN E. JOHNSON.
